US0D1047937S

(12) **United States Design Patent** (10) **Patent No.:** **US D1,047,937 S**
(45) **Date of Patent:** **** Oct. 22, 2024**

(54) **CONTROLLER**

(71) Applicant: **TIMOTION TECHNOLOGY CO., LTD.**, New Taipei (TW)

(72) Inventor: **Bo-Yen Shen**, New Taipei (TW)

(73) Assignee: **TIMOTION TECHNOLOGY CO., LTD.**, New Taipei (TW)

(**) Term: **15 Years**

(21) Appl. No.: **29/887,898**

(22) Filed: **Mar. 25, 2023**

(51) LOC (14) Cl. **14-03**

(52) U.S. Cl.

USPC **D13/168**; D13/133; D13/162; D13/164; D13/171; D13/174; D14/217; D14/218; D14/454

(58) **Field of Classification Search**

USPC D13/123, 133, 152, 154, 156, 158, 160, D13/162, 1, 163, 164, 168, 169, 170, 171, D13/173, 174, 177, 178, 184, 199;

D14/128, 188, 218, 358, 385, 456, 496

CPC H02J 13/00022; H04L 2012/2841; H04L

67/025; H04L 2001/0097; H04M 11/007;

H04M 1/72415; A47C 31/008; A61G

2203/12

(57) **CLAIM**

The ornamental design for a controller as shown and described.

DESCRIPTION

FIG. 1 is a perspective view of a controller showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is second perspective view showing the controller. The broken lines shown in the figures are for the purpose of illustrating portions of the controller and form no part of the claimed design.

1 Claim, 8 Drawing Sheets
